[57] ABSTRACT

A head assembly for continuously removing dust accumulating on margins of shoe soles as a result of operations carried out on the margins by a rotary tool. The head is adapted to fit over the tool and includes a feed or guide slot for introducing marginal portions of soles to the interior of the head. The feed slot is located intermediate of air intake means and air exhaust means, and adjustment means is provided for orienting a sole as fed through the feeding slot.

DUST REMOVAL MEANS

BACKGROUND OF THE INVENTION

Various operations are commonly carried out on margins or marginal portions of unattached shoe soles, that is prior to their assembly with shoe uppers. They may be roughened to facilitate adhesive attaching with the uppers and/or shaped to provide them with attractiveness in finished appearance. The latter may include reducing the edges to give a skived, beveled, rounded, reduced or other desired edge contour.

The operations presently practiced to effect margin roughing, shaping, etc., are generally of a continuous or automatic nature using rotary cutting or abrading tools, singly or in combination. An example of the apparatus used is disclosed in U.S. Pat. No 3,435,474 issued Apr. 1, 1969. That type of operation has been accompanied by an accumulation of dust or fine material on the marginal portions of the soles so operated on. A serious problem arises as a result in that the dust on the margin interferes with convenient and successful practice of operations to follow, a prime example being the operation of adhesive attachment of the roughened sole to a shoe upper. Others include the applications of various finishing materials, colorants, etc. The problem of dust accumulation and adherence is particularly acute where the soles operated on are of a composition and the incidence of use of composition soles is very large and continually increasing.

An incidental problem which arises relates to the rotary abrading tools themselves. With high speed and continuous operation, particularly on composition soles, the tools too become adversely affected, losing their cutting efficiency. A large measure of that can be attributed to dust from the soles and elsewhere becoming compacted on the operating surface of the tool. This is aggravated in the case of composition soles due to the presence of resins used in formulating the compositions from which the soles are molded. The resins are often thermoplastic in nature and may become fluidized by frictional heat created by the operation. As a result the efficiency of the tools, as well as the apparatus using them, and the margin detail on soles produced by their operation are all adversely affected.

It is an object of this invention to provide means for expeditiously removing or eliminating dust otherwise accumulating on margins of shoe soles resulting from abrading, cutting, or similar operations carried out by rotary tools on the said margins.

It is another object to provide means to remove dust accumulating on operating surfaces of rotary tools for abrading, cutting, and otherwise processing margins of shoe soles.

Those and other objects of the present invention are attained in a dust removal head assembly adapted for use with rotary tools designed to abrade, cut, skive, shape, reduce, trim or otherwise finish margins of shoe soles. The illustrative head assembly comprises a casing or hood adapted to fit over a rotary tool, air intake and air exhaust means for the hood, sole feeding or guiding means communicating with the interior of the hood located intermediate of the air intake and air exhaust means, and means for providing the sole with a particular orientation as it is fed through the feeding means.

A further feature of the arrangement includes sole feeding or guiding means in the form of a feed or guide

slot formed between a pair of lips extending between a pair of generally normally disposed ends provided in the head or hood. One of these ends, which may be referred to as a leading end, may serve as an abutment against which the sole is directed on feeding. The feed slot is provided in a rotatable collar portion of the head or hood which portion is rotatable in response to the edge of the sole bearing on the leading end or alternatively against a proximately located abutment. By providing the rotatable collar with a spring or other means which resists rotation, or causes the collar to rotate reversely after being advanced, the leading end of the slot generally follows the contour of the sole being progressively passed therethrough. The leading end of the feed slot may be provided with an outline shape generally complementing that of the edge of the sole and, as indicated previously, it may also be provided with a wear resistant insert or pin acting as the abutment. The other end of the feed slot, which may be referred to as the following end of the feed slot, may also be shaped to generally complement the outline shape of the sole edge.

The length of the feeding slot may be chosen to allow a maximum portion of the sole margin to be introduced into the slot at any time, while at the same time it is desirable to choose the length so as to minimize as much as possible the space formed between the following end of the feed slot and the sole edge opposing the same. This can, however, be assessed only in a general way because of the changing curvature of outline contour of soles following around the periphery of the same. To some extent feed slot length will be determined by the radius of the collar portion of the hood and the thickness of the collar portion section, but is generally related to the outline shape of shoe soles to be operated on.

The width of the feed slot, between its lips, is chosen to accommodate soles to be fed through the same. Further, the slot may be of such width as to provide for or accommodate soles of considerably different thicknesses as measured between tread surfaces of a sole. Parenthetically, it will be understood that a sole has two tread surfaces, the flat, plane surface S, constituting top and bottom and bounded peripherally by the side edge faces of the sole.

It has been discovered that dust removal at the marginal portion of a sole may be accomplished expeditiously and in continuous fashion by directing the tread surface facing in the direction of the exhaust means into contact with the corresponding lip of the feed slot and maintaining that relationship as the sole is fed through the same. The fact that there is a space formed between the opposite tread surface and the slot lip confronting it does not materially affect the efficiency of the dust removal operation. As a consequence, the slot may, as indicated previously, be of sufficient width between lips to accumulate soles in a broad range of thicknesses.

Positioning means are provided for directing and maintaining a tread surface in contact with the corresponding feed slot lip as the sole is being fed through the feed slot. That tread surface is the one facing in the direction of the air exhaust means. Again the fact that the tread surface opposite to that being maintained against the indicated feed slot lip may be removed

some distance from the lip of the feed slot corresponding to it, will not noticeably interfere with the effective capacity of the head to remove dust from the sole margin, and do so expeditiously and in a continuous, automatic manner.

According to another feature of the invention the head is arranged so that the air intake means serves to direct a stream of cooling air over the operating surface of the rotary tool when the latter is located within or fitted to the interior of the hood. In that manner accumulation of dust on the operating surface of the tool is greatly reduced if not effectively prevented.

BRIEF DESCRIPTION OF THE DRAWINGS

FIG. 1 is a front view partly in section illustrating an embodiment of the dust removal head assembly of this invention in which a hood is fitted over a rotary tool operable on a sole extending through a feed slot;

FIG. 2 is a side view partly in section illustrating the hood of FIG. 1 in combination with means to orient feed of a sole within the feed slot;

FIG. 3 is an exploded perspective view of the assembly shown in FIG. 1;

FIG. 4 is a top view partly in section taken along the line IV—IV of FIG. 1 and showing the sole at an early stage of feed within the feed slot;

FIG. 4a is a view corresponding to that of FIG. 4 but with the sole at a later stage of feed within the feed slot, and;

FIG. 5 is a partial front view of a rotatable collar showing the feed slot with a sole fed thereto.

DETAILED DESCRIPTION OF THE ILLUSTRATED EMBODIMENT

While the dust removal head assembly of the present invention may be used in conjunction with a wide variety of rotary tools adapted to operate on shoe soles, it has particular application, for instance, in machines of the type disclosed in U.S. Pat. No. 3,435,474 issued Apr. 1, 1969, to Herman A. Imhof. In that context, it is intended that that patent be included by reference.

As shown particularly in FIGS. 1-3, the dust removal head of the present invention comprises a hood 10 having a hollow interior 12 adapted to fit over a rotary tool 14, see specifically FIGS. 1 and 2. The hood 10 includes a main hood portion 15 cooperating with a rotatable annular collar portion 16, the latter having formed therein a feeding slot 18 (FIG. 5) located intermediate of an air intake means or collar end 20 and air exhaust means or collar end 22, provided on the collar. The air exhaust end 22 communicates by means of a duct or hose 24 with a vacuum pump, not shown.

The main hood portion 15 of hood 10 is shown constituting a block 26 with an upstanding boss portion 26a, both enclosing hood interior 22. The block 26 includes a circular recess 28 into which a double race ball bearing ring 30 fits. Bearing retainer plate 32, having a circular cut out center 34, secures the ball bearing ring 30 within channel 28. The inner race of the ball bearing ring 30 clears the cut out center 34 and the plate 32 is secured to the bottom surface of block 26 by means of cap screws 36 (FIG. 3) leading through plate holes 38 into holes, not shown, correspondingly located in the bottom surface of the block 26.

The hood 10 receives the rotatable collar portion 16 in the form of a block 40 and an upstanding boss portion 40a, thereby occupying the lower portion of hood interior 12. The boss portion 40a is press fit to the interior of the inside race of ball bearing ring 30 to allow for rotation of collar portion 16 relative to main hood portion 15. A flat shouldered surface 44 located at the inner top surface of block 40 serves as a bearing surface for the surface of the inside race of ball bearing ring 30.

The collar block 40 includes spring groove 46 into which tension spring 48 fits and is attached between pins 50 and 52 (FIG. 1). Pin 50 is attached to the collar portion 16 and the pin 52 is attached to the main hood portion 15. The spring 48 serves to yieldingly resist rotation of collar portion 16 relative to the main portion of hood 10. The amount of loading in spring 48 is sufficient to allow the collar portion 16 to be rotated in one direction by a sole S being fed or directed horizontally through feed slot 18 while at the same time being capable of rotating the collar 16 reversely to a starting location when a sole edge no longer bears on the collar or after a sole S has been completely advanced through feed slot 18. The bottom end of the collar portion 16 serves in this case as the air intake means 20. As shown, the end 20 is positioned below rotary tool 14, or, to state it differently the tool 14 is fitted entirely within the interior 12, so that the intake air is directed over tool 14 and particularly over the operating surface of the tool 14. In this example the rotary tool 14 is shown as an abrading stone provided with a grooved surface with which to provide a rounded edge face on the sole S. Note in that regard that the tool 14, and specifically the operating surface of the same is aligned with feed slot 18 so that the sole S as advanced through feed slot 18 may be operated upon accurately by tool 14.

The feed slot 18 is defined by a pair of spaced, horizontal lips 54 and 56 in collar portion 16, see specifically FIG. 5. Top lip 54 is part of the bottom flat surface of an annular projection 58 carried on collar portion 16. That arrangement serves to provide a relatively large surface against which to guide by contact the top tread surface of sole S being fed through feed slot 18. In that regard, the feed slot should extend so that a portion of the top or reference tread surface of the sole being operated upon will remain in contact with top lip 54, that is the lip contacted by the tread surface facing the air exhaust means, for some distance behind the operating locality of the rotary tool 14. The width of feed slot 18 between the lips 54 and 56 is such as to accommodate soles of different and/or varying thicknesses, see again FIG. 5. This takes advantage of the discovery that effective dust removal is obtained by providing extended contact as described between the tread surface facing the exhaust means and corresponding feed slot lip 54. The length of feed slot 18 is defined between a leading end 60 (FIGS. 4, 4a), against which the edge fact of advancing sole S is directed and following end 62, see FIGS. 4 and 4a specifically. Leading slot end 60 may serve directly as an abutment surface or gage up against which the advancing edge face of a sole S is contacted, or optionally a hardened abutment pin 64 may be proximately located to end 60 for that purpose. The abutment pin 64 which may be of hard steel alloy, carborundum, etc., is included to ex-

tend the effective wear life of the part formed with the feed slot 18. Otherwise, the leading edge 60 may become worn by the soles and the entire part must then be replaced. Machines of the type referred to are generally automatic and operated at high speeds; as a consequence a high degree of wear can take place within a short operating period. The slot ends 60 and 62 are shown concave and contoured to generally complement the outline curved shape of a sole S due to edge face curvatures of the peculiar outlines of soles, which continually vary progressively over their peripheries in any given sole.

As indicated particularly at FIGS. 4 and 5, a sole S is advanced past the tool 14 and through the slot 18 while maintaining contact between an edge face of the sole and the abutment pin 64 when used. This causes the collar portion 16 to be rotated in a counterclockwise direction as viewed in those figures. The spring 48 operates to generally maintain that contact and, with sole S passed entirely through slot 18, the collar portion 16 is caused to return, by rotation in the opposite direction to a rest or starting position.

The margin of the sole S is shown in FIG. 1 being advanced over a fixed work support 65 and into and through feed slot 18 by a pair of positive drive rolls 66 and 68 in the manner disclosed in the previously identified Imhof patent. In order to provide and maintain the desired orientation of the sole during its advance through feed slot 18, that is as previously described, by having the top tread surface in contact with the top lip 54 of the feed slot 18, means are provided by which to adjust the hood 10, and the carrying slot 18, in heightwise relation to sole S. The upper block 26 of hood 10 is formed with a T-slot 70 into which slidably fits complementary shaped post 72 thus allowing the hood 10 to be adjusted heightwise. Post 72 extends upstandingly from a cap plate 74, the latter provided with an open recess 76, see FIG. 3, into which the top portion of a motor 78 fits with its drive shaft 80 connecting tool 14 with motor 78 extended upward through recess 76. An exhaust vent 82 for motor 78 is provided in cap plate 74, see FIG. 1. The cap plate 74 is attached onto a stanchion 84, by means of a pair of cap screws 86, and at its lower end stanchion 84 is attached to and carried by a swingable tool arm 88 of the type disclosed in the previously identified Imhof patent. The motor 78 is also attachably held by tool arm 88.

The amount of adjustment or orientation required for a given sole S fed through feed slot 18 to effect adequate dust removal from the same may be considered relatively small, but at the same time is very critical. As a result provision is made to finely adjust the heightwise positioning of the head 10, as it relates to the contact to be provided between an upper tread surface of sole S and the upper lip 54 of feed slot 18. The contact so provided should be fairly close while at the same time allowing the sole S to be advanced through the slot. To facilitate feeding upper lip 54 may be provided with a permanent lubricant such as a coating of a fluorocarbon polymer or a temporary lubricant such as a silicone spray or compound or the like.

An effective arrangement for accomplishing the required hood adjustment heightwise relative to a sole S within feed slot 18 is shown particularly at FIGS. 1 and 3. A cover plate 90 having a threaded hole 92 for

accepting a threaded shaft 94 of height adjustment screw 96, is attached to the upper surface of the hood block 26 so that it covers the top opening of T-slot 70. To secure the plate 90, cap screws 98 are led through holes 100 in the cover plate 90 and threadedly extended into holes 102 in the block 26. A set screw 104 (FIG. 3) for locking the screw 96 in a selected position, and specifically upper shank portion 94 of the same relative to the plate 90, is threaded into the side of plate 90.

Adjustment screw 96 includes a lower threaded stem portion 106 which fits into threads provided in height adjustment insert 108, and the latter in turn slidably fits into bore 110 formed in the post 70. A guide slot 111 is provided on the insert 108. The insert 108 is fixedly positioned angularly within bore 110 of the post 72 by means of a retaining pin 118 carried by the post. A guide pin 112 extends slidably through a vertical slot 124 provided in a clip 114 and into the slot 111. Guide pin 113 fitted into guide slot 111 of insert 108 serves to facilitate proper positioning of that as well. Spring clip 114 is removably attached to the post 70 by means of a pair of parallel ears 120 which are slidably received in slots 122 formed on opposite sides of the post 70. Rotating adjustment screw 96 serves, since the insert 108 can not rotate and the post 72 is not movable vertically, to lift the plate 90 with the hood assembly 10 and hence to adjust the hood feed slot 18 heightwise in relation to the sole S being fed therethrough. More specifically, and as described previously the desired orientation or adjustment is directed to providing contact between an upper tread surface of sole S and the top lip 54 of feed slot 18. The top lip 54 is that closest to the air exhaust means 22 and complements the tread surface facing air exhaust means 22.

In operation, the head 10 is assembled over a rotary tool carried on a shoe machine designed to operate on margins of shoe soles, as for example, the automatic or continuous machine disclosed in the above identified Imhof patent. The head 10 is then adjusted in the direction of the axis of rotation of the tool to position a gage surface relative to soles advanced into the feed slot 14 so that the upper tread surface of the sole is in slidable contact with the upper lip 54 of slot 18. Soles are then advanced continuously and manually on the support 65 or automatically through the machine in the manner described in the Imhof patent.

It will then be seen that the objects set forth above, including those made apparent from the preceding description, are efficiently attained and, since certain changes may be made in the above dust removal head assembly without departing from the scope of the invention, it is intended that all matter contained in the above description or shown in the accompanying drawing shall be interpreted as illustrative and not in a limiting sense.

Having thus described my invention, what I claim as new and desire to secure by Letters Patent of the United States is:

1. A head assembly for continuously removing dust accumulated at shoe sole margin from the operation of a rotary tool along said margin comprising a hood adapted to fit over the rotary tool, sole feeding means essentially defined by a pair of lips spaced to form a slot communicating with the interior of the hood to accom-

modate continuous feeding of a marginal portion of a sole therethrough, the sole feeding means being positioned intermediate of means for intaking air to said hood and means for exhausting air from the same, and means for positioning one of the lips relative to the tread surface of a sole fed through the feeding means to direct a tread surface on the marginal portion facing said exhaust means against the corresponding adjacent lip of the feeding means.

2. A head assembly according to claim 1 wherein the sole feeding means is a slot defined between lips provided in a collar portion of the hood, the collar portion being essentially rotatable toward with respect to a main portion of the hood in response to the sole fed therethrough with the sole edge being driven against an abutment surface located to an end of said slot.

3. A head assembly according to claim 2 wherein the abutment is a pin of circular cross-section which extends between said lips.

4. A head assembly according to claim 3 wherein the pin is formed of carborundum material.

5. A head assembly according to claim 2 wherein the

collar portion is provided with yieldable means for rotating the same reversely to a starting position after a sole margin has completely passed through the said slot.

5 6. A head assembly according to claim 5 wherein the means for rotating the collar backward is a spring attached at one point to said collar portion and at a second point to the main portion of said hood.

7. A head assembly according to claim 1 wherein the sole feeding means is positioned so that a sole fed therethrough registers on an operating surface carried on a rotary tool fitted to the interior of the hood.

8. A head assembly according to claim 1 wherein the means for intaking air to the hood is located so as to direct the air over the operating surface of a rotary tool fitted to the interior of the hood.

9. A head assembly according to claim 1 wherein the means for exhausting air from the hood includes a duct attached thereto and to means for generating at least a partial vacuum.
